Filed Mar. 2, 1960, Ser. No. 59,590

Term of patent 14 years

(Cl. D45—1)

Fig. 1 is a top plan view of a gem setting showing our new design as applied to a finger ring;

Fig. 2 is a side elevational view thereof;

Fig. 2A is a bottom plan view thereof;

Fig. 3 is a front elevational view of our new design for a gem setting as applied to a pendant;

Fig. 4 is a side elevational view thereof;

Fig. 5 is a front elevational view of our new design for a gem setting as applied to a stick pin; and

Fig. 6 is a side elevational view thereof.

The broken line portions in the drawings of a finger ring, pendant and chain, and stick pin are for illustrative purposes only.

The gem is shown schematically in light full lines for illustrative purposes only.

This application is a continuation-in-part of our pending application Serial No. D.55,941, filed May 18, 1959.

We claim:

The ornamental design for a gem setting, as shown and described.
